UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP-CAR DOOR-OPERATING MECHANISM.

Application filed September 2, 1927. Serial No. 217,224.

My invention relates to improvements in dump car door operating mechanisms and the like and especially related to that general type of a car having bodily movable and rotatable shaft adapted to travel from a position beyond the free edge of the door to a supporting position beneath the free edge thereof.

In cars of the identified type, it has been customary to provide a shaft mounted for movement in elongated slots, said shaft being connected to the door by a series of flexible connections adapted to wind around the shaft to raise the door, the shaft thereafter moving beneath the door by a combined sliding and rotary movement, serrated members being respectively provided on the shaft and door mainly for the purpose of providing a tooth-like engagement whereby the shaft may be displaced outwardly from beneath the door by a partial rotation of the shaft during release of the door. In mechanisms of this type, it has been customary to attach the flexible connection on the under- side of the door inwardly beyond the limit of movement of the shaft whereby, as the shaft comes into engagement with the door, a continued winding action of the flexible element on the shaft will cause the latter to travel inwardly beneath the free edge of the door and thereby exert a wedging action between the door and the lower face of the elongated slot in which the shaft travels, to force the door to a fully closed position by said wedging action. It is also customary to provide a series of such doors, generally four doors to a section of shaft, and two flexible connections per door, thereby making eight connections to a shaft, and it has been found by experience that as such connections do not always wind in the same ratio and also vary in length there is presented an unequal door lifting action as the shaft is moved beneath the door, in certain instances the links binding and fouling between the door and the shaft.

It is an object of my invention to remedy this deficiency by incorporating with the flexible connection, a spacing element which will have its point of attachment with the door inwardly of the shaft and its point of attachment with the flexible sections of the connection beyond the shaft whereby the flexible connection will always bear a fixed relation to the free edge of the door.

Another object of my invention is to provide an improved locking mechanism for the shaft whereby reverse rotation of the shaft will be prevented as the door is raised and outward bodily movement of the shaft in the slots guarded against.

My invention also consists of certain other improvements as will be more particularly pointed out hereinafter and claimed.

In the drawings forming a part of this specification, Fig. 1 is a plan view of a portion of a car showing my improvements in connection therewith, said view including one-half the width of the car and showing one of the drop doors with the cross beams associated therewith. Figure 2 is a transverse sectional view taken on a line corresponding substantially to line 2—2 of Figure 1, said view illustrating the door in closed position. Figure 3 is a longitudinal elevational sectional view of that portion of the car shown in Figure 1 and taken on line 3—3 of Figure 1, the lower chord of the side frame being eliminated for the purpose of more clearly showing the parts. Figure 4 is a view similar to Figure 2 except that the door is illustrated in open instead of closed position. Figure 5 is an enlarged detail view of a portion of the car showing the outer end of the crossbearer as viewed on line 5—5 of Figure 3, said view illustrating the shaft moved into initial engaging position with the door. Figure 6 is a view of the door bracket casting on an enlarged scale as viewed on line 6—6 of Figure 3. Figure 7 is a vertical elevational longitudinal view of a portion of the car near the end thereof and illustrating the door locking and rotating mechanism. Figure 8 is a vertical end view of that portion of car showing the construction illustrated in Figure 7 as viewed from right to left, the parts being illustrated with the door in closed position and the mechanism locked beneath the door. Figure 9 is a view similar to Figure 8 except that it shows the parts in unlocked position with the shaft moved outwardly beyond the free edge of the door. And Figure 10 is a perspective view of the pawl retaining member.

In said drawings, I have shown my invention as applied to a drop bottom car of a form well known in the art, cars of said type generally having a plurality of doors on each side of the center sill, the number

of which may be varied as desired, said doors being generally operated from the end of the car in sets of several doors each. In my drawings I have considered it necessary to indicate only one of such doors on one side of the center sill and the description is confined to the same, it being understood that such description will also apply to the various doors of a series.

10 The car, as shown, is provided with a center-sill indicated at 10, crossbeams of the under-frame 11, crossbeam top cover plates 12, side stakes 13, car side bottom chord 14 and car side wall 15. The floor of the car, or such 15 portion of it as desired is formed by floor doors generally indicated by the reference character A, the latter being pivotally attached along their inner edges as indicated at 16 to suitable hinge butts 17 which in 20 turn are suitably secured to the centersill 10. The crossbeam top cover plates 12 along each side edge of the door and the car side bottom chord 14 are each preferably extended to overlap the said door A to provide 25 an overhanging abutment for the side and front edges of the door when in closed position. As will be understood there will generally be one door A between each pair of the cross members of the underframe 30 on each side of the centersill. Each door A is preferably reinforced with depending flanges along its rear, side and free edges as respectively indicated at 18, 19 and 20 and also by transverse and longitudinal beams 35 21 and 22, the latter being preferably in the form of a Z-bar brace spaced inwardly a short distance from the free edge of the door. The crossbeams 11 of the underframe are apertured at their outer ends so as to 40 accommodate the longitudinally extending operating shaft 23. The latter extends through the apertures of the crossmembers and through similarly elongated openings provided in bearing castings 24 which are 45 riveted or otherwise secured to the crossbeams.

In the arrangement shown, each elongated bearing slot is formed with a substantially straight bearing portion 25 and a curved depressed portion 26, the latter being disposed in the outer end of the slot and beyond the free edge of the door. Intermediate the crossbeams, the shaft is provided with a plurality of winding sheaves 27 fixed rigidly 50 on the shaft. Each said winding sheave is formed with spiral guideway 28 and includes at one end a serrated wheel 29 and at the opposite end an outstanding integral bracket 30 having a perforation 31. In 55 alignment with each said serrated wheel 29, there is disposed on the door a bracket 32 having a curved nose 33 projecting slightly beyond the outer end of the door. Said bracket is formed on its underside with serrated surface 34, the latter being adapted to

register with the serrated wheel 29 when the shaft is in contact with the door. Said bracket 32 is disposed intermediate the front flange and the Z-bar brace 22 of the door and secured to the door plate and to the 70 Z-bar brace. Adjacent the serrated surface 34 there is provided a recess 35 defined by side walls 36 and 37, and an upper wall 38, said last named wall 38 being spaced a short distance below the door plate. 75

Connections are connected to the door and shaft respectively for the purpose of raising the door by a rotation of the shaft and thereafter bringing the shaft to a supporting position beneath the door, said connections including a flexible section 39, such as a chain, and a pivoted link member 40, the former being attached at one end to the bracket 30 of the sheave 27 by means of an adjustable eyebolt 41, and, at its opposite end, to the 80 pivoted link member 40, the connection between the sections 39 and 40 providing a pivotal connection around the end link of the flexible section as indicated at 42. 85

Said link 40, which is adapted to lie in the 90 recess 35, is pivoted to the bracket 32 at 140 and is restrained against sidewise movement by the walls 36 and 37 but permitted to have pivotal movement at right angles to the longitudinal axis of the shaft about said 95 pivot 140. Said link, on its upper surface, is formed of convex shape as indicated at 43 and of concave shape on its under surface as indicated at 44, said surfaces 43 and 44 being adapted to contact respectively with 100 upper wall 38 of bracket 32 and winding sheave 27.

As the flexible connection 39 winds around the spiral guideway 28 during the lifting of the doors and until such time as the serrated 105 wheel 29 on the shaft moves into contact with the serrated surface 34 on the curved nose 33 in the manner indicated in Figure 5, the convex surface 43 of link member 40 is in contact with the upper wall 38 of recess 110 35 and said link, in effect, provides a non-serrated extension which projects beyond the serrated surface 34 on the door and beyond the serrations on the periphery of the wheel 29 on the shaft. 115

The operation of the lifting and supporting mechanism is as follows, first assuming a closing movement of the door, particular reference being had to Figure 5 of the drawing. As the link chain section of the flexible 120 connection is wound around the shaft while the latter is in the outermost portions of the slots in supporting brackets, the door will be gradually elevated until the condition is reached shown in Figure 5, at which time the 125 serrated nose on the door engages with the serrated wheel 29. During this lifting operation of the door and at the condition shown in Figure 5, the link 40 will bear against the wall 38 of the bracket casting. 130

When the parts have reached the condition shown in Figure 5, the shaft, as it continues its bodily movement underneath the door will fulcrum for a short distance about the 5 pivotal point of connection 42 with the effect of a lever arm of a length indicated by the line 45, this action being permitted by reason of the fact that the outer end of the link 40 is curved as indicated at 46 concentrically 10 with the pivotal point of connection 42. As further movement of the shaft takes place inwardly beneath the door, the fulcrum action referred to will elevate the door still further and the link 40 will accommodate 15 itself relatively to the shaft by pivoting about the pivotal center 140 until the condition is reached as shown in Figure 2, at which time the door is fully closed and the concave surface 44 of the link 40 will be supported 20 upon the spiral guideway on the shaft.

As will be understood from the previous description, the link 40 is restrained against sidewise movement, that is, movement lengthwise of the operating shaft and is 25 confined to movement in a vertical plane, that is, in a plane perpendicular to the axis of the shaft, by reason of the link 40 being confined between the walls 36 and 37. This construction, coupled with the fact that the 30 end link of the flexible section 39 is so pivoted to the link 40 that said end link cannot twist or turn, insures against any fouling of the flexible connection with the free edge of the door. As is well known, when a link 35 connector winds around a spiral drum, there is a constant tendency for the links to twist so that the position of any particular link cannot be definitely controlled during any operation. With my construction, the end 40 link of the flexible chain section can neither engage the free edge of the door, since it is connected to the heavy link 40 at point 42, nor can it twist and hence the supporting 45 point of contact in raising the door and while the shaft first passes beneath the edge 50 of the door is between the link 40 and the bracket to which it is attached. Further, since the link 40 is confined to movement in the plane perpendicular to the shaft, a straight line pull on the end link of the chain 55 section is always assured at the critical time when the serrated nose piece and serrated wheel come into engagement and the wedging or leverage action as the shaft passes under the door, takes place. Further, due to the fact that the heavy link 40 has a smooth surface engagement with the spiral drum when supported on the latter a limited degree of sliding movement between said link 60 40 and the shaft 23 is thereby provided so that the said two parts may relatively adjust themselves. While the description of operation has been confined to one operating linkage, it will be understood that it applies 65 equally well to all sets and that, by reason

of the heavy links 40, the end links of all chain sections will be held in the same relative positions with respect to the edge of the door.

Referring now more particularly to the 70 shaft locking and rotating mechanism shown in Figures 7 to 10, said mechanism is preferably located on the end of the car, the operating shaft 23 being extended beyond and through the end sill 47 where the shaft is 75 fitted with a ratchet wheel 48. Cooperating with said ratchet wheel 48 is a pivoted lever 49 mounted adjacent the ratchet wheel and having a plurality of pawls 50 and 51 pivotally mounted thereon, said pawls being 80 mounted for engagement with the ratchet wheel mainly on the underside thereof or that portion of the wheel lying below a horizontal plane passing through the axis of the shaft. Said lever is formed adjacent its 85 lower end with a lever receiving socket 52 of the usual form, whereby the shaft may be rotated.

Secured to the end sill above the ratchet wheel is a bracket 53 having a plurality 90 of fulcrum posts 54 and 55, adapted to form fulcrums for a pivoted pawl 56 and a pawl retaining member 57. Said last named members are retained on their respective pivots by rivets 58 and washers 59. The pawl 56, which is pivoted above the ratchet wheel 48 and to one side of a vertical line passing through the axis of the shaft, is formed on its outer side with a cam-shape 100 contour 60. Cooperating with said cam-shape portion 60 to lock the pawl 56 in position relatively to the ratchet wheel 48, is the pawl retaining member 57 (see Figure 10) 105 said last named member being of substantially angle formation including a shank portion 61 and an inwardly extending end portion 62 adapted to embrace the cam shape portion 60 when the shaft is in supporting position beneath the door. The arrangement of locking means extending from fixed 110 points on the car structure is particularly advantageous for use with bodily movable shafts as it compels the complete closing of the doors with the shaft brought to a definite position before final locking of the shaft 115 is effected. Furthermore, the shaft is not only effectively locked against rotation but it is also secured against bodily movement.

Assuming the parts in closed position and it is desired to open the doors, the operation 120 is as follows: The pawl retaining member 57 is rotated in a clockwise direction and brought to an over-balanced position clear of the pawl 56, and the pawl 56 rotated clear of the ratchet wheel 48 and also brought to an over-balanced position, the position of these parts then being as indicated in Figure 9. The operator then inserts a bar in the socket 52 and positions pawl 50 in engagement with the ratchet wheel and rotates 125 130

the shaft in a clockwise direction, thereby moving the same outwardly in the slots from supporting position beneath the door by reason of the inter-engagement between serrated wheels 29 on the shaft and serrated surfaces 34 on the doors. The outward movement of the shaft is continued until arrested in the curved depressed portions 26 of the bearing castings 24 when the weight 5 of the doors and lading will rotate the shaft until the door is fully opened. To close the door, the operator positions locking pawl 56 into engagement with the ratchet wheel 48, inserts removable bar in the socket 52 of 10 the lever, positions pawl 51 in engagement with the ratchet wheel 48, and rotates the shaft in an anti-clockwise direction as viewed in Figure 8. When the shaft is thus rotated one step, it is evident that the locking pawl 56 will hold the shaft 24 by means 15 of ratchet wheel 48 and retain it in whatever position it may have been adjusted while the operator moves the bar in the opposite direction to engage the pawl 51 with the next tooth of the operating ratchet. These 20 operations are repeated until the doors have been moved to a fully closed position and the shaft moved to a supporting position under the door when the operator will throw 25 the pawl locking member 56 into locking position as shown in Figure 8.

While I have herein shown and described what I now consider the preferred manner of carrying out my invention, the same is 30 merely illustrative and I contemplate all changes and modifications that come within the scope of the claims appended hereto.

I claim:—

1. In a railway car door mechanism, the 35 combination with a door; of a lifting shaft, said shaft being movable into supporting position beneath the door when the latter is closed; a connection from the shaft to the door, said connection including a rigid link 40 pivotally mounted beneath the door and extending outwardly towards the free edge of the same and beyond the shaft when the latter is beneath the door; and serrated engaging portions formed on the shaft and the door respectively.

2. In a railway car door operating mechanism, the combination with a car door; of a winding shaft adapted to lift said door, said shaft being movable to a supporting position beneath the door; a connection extending 45 between the shaft and the door, said connection including a rigid link pivotally secured to the door and a series of flexible links secured to the opposite end of said link and also to the winding shaft; serrated bearings on the door and on the shaft; and limiting means associated with the link and the door for the purpose of retaining the link in fixed relation to the serrated bearings on the door.

3. In a car door operating mechanism, the combination with a door; of a winding shaft, said shaft being adapted to raise the door, said shaft being movable to a supporting position beneath the door; a connection from the shaft to the door, said connection embodying a rigid link and a flexible section, said rigid link being mounted beneath the door and said flexible section outwardly of the door. 70

4. In a car door operating mechanism, the combination of a door lifting and supporting shaft, said shaft being movable into supporting position beneath the door when the latter is in closed position; and a connection from the shaft to the door, said connection including a rigid link pivotally mounted upon the door and a flexible link connection extending between the shaft and the outer end of the said link, the connection between the rigid link and the flexible link being at a point outwardly of the shaft when the latter is in locked position beneath the door. 75

5. In a car door operating mechanism, the combination with a dumping door; of a winding shaft adapted to raise the door, said shaft being movable to a supporting position beneath the door; a bracket on the door, said bracket having a curved nose and serrations formed thereon; a roller on the shaft having serrations adapted to engage with the serrations on the nose of the door; and a flexible connection connecting said shaft and door, said flexible connection including a pivoted link having one end pivotally mounted on the door bracket and having its opposite end projecting beyond the serrations of the door. 90

6. In a car door operating mechanism, the combination with a dumping door; of a winding shaft, said shaft having bodily movement to a supporting position beneath the door when the latter is in closed position; of a connection from the shaft to the door, said connection including a rigid link section and a flexible link section; serrated surfaces respectively formed on the door and shaft whereby a gripping engagement is provided between the shaft and door for the purpose of displacing the shaft from its supporting position beneath the door. 105

7. In a car door operating mechanism, the combination with a door; of a winding shaft, said shaft being bodily movable to a supporting position beneath the door when the latter is in closed position; a connection from the shaft to the door, said connection including a rigid link pivotally mounted upon the door and a flexible section pivotally connected to the rigid link, said last named flexible section being adapted to have transverse and longitudinal movement relatively to the shaft; and means associated with the rigid link for restricting its movement to 110 120 125 130

a plane at right angles to the longitudinal axis of the car.

8. In a car door operating mechanism, the combination with a winding shaft, said shaft being adapted to have a bodily movement to a supporting position beneath the door when the latter is in closed position; of a bracket fixedly mounted upon the door, said bracket having a serrated surface formed integrally therewith; a serrated surface fixedly mounted upon the shaft, said surface being adapted to register with the serrated surface on the door; a rigid link pivotally mounted upon the door adjacent the serrated surface on the door, said link having a portion thereof projecting outwardly beyond the door; and a flexible connection extending from the end of said link to the shaft, said flexible connection being adapted to have transverse and longitudinal movement relatively to the shaft.

9. In a car door operating mechanism, the combination with a dumping door; of a winding shaft, said shaft having a bodily movement to a supporting position beneath the door; connections from the shaft to the door; means for imparting movement of rotation of the shaft; means for locking the shaft against unwinding movement; and means for locking the shaft against outward bodily movement.

10. In a car door operating mechanism, the combination with a dumping door; of a winding shaft, said shaft being adapted to be moved bodily to a supporting position beneath the door by a movement of rotation; means for imparting a movement of rotation to the shaft; means for locking the shaft against an unwinding movement, said last named means comprising: a ratchet wheel fixed to the shaft, a pawl having a stationary pivot on the car structure and mounted above the shaft, said pawl being adapted to engage with the ratchet wheel throughout the entire movement of the shaft; and means for locking the pawl in a fixed relation to the car structure and to

the shaft whereby outward movement of the shaft is prevented.

11. In a car door operating mechanism, the combination with a dumping door; of a winding shaft, said shaft being movable bodily by a movement of rotation to a supporting position beneath the door; a ratchet wheel fixedly mounted upon the shaft; means movable with the shaft for engaging the lower portion of said wheel for imparting a movement of rotation to the shaft; means acting upon the upper portion of the ratchet wheel for locking the shaft against an unwinding movement, said means including a pawl pivotally mounted upon the car structure; and means for locking said locking pawl in a fixed relation to the ratchet wheel, said last named means including an L-shaped locking member adapted to embrace the locking pawl and maintain the latter in a fixed relation to the ratchet wheel and to the car structure.

12. In a dump door operating mechanism for vehicles such as railway cars, the combination with a pivoted door; of an operating shaft positioned adjacent the free edge of the door, said shaft being supported by the vehicle structure and adapted for rotation and bodily translation to a door supporting position beneath the free edge of the door; and connecting means between said shaft and door, said means including an element attached to the door adjacent its free edge and movable relatively thereto only in a plane perpendicular to the axis of the shaft, and a flexible connector attached at one end to the shaft adapted to wind thereon and, at its other end, pivotally attached to said element at a point to prevent contact between the door and the end unit of said flexible connector which is attached to said element while the shaft is moving under the door during a closing operation.

In witness that I claim the foregoing I have hereunto subscribed by name this 27th day of August, 1927.

ARGYLE CAMPBELL.
